UNITED STATES PATENT OFFICE.

WALTER H. WHITESIDE, OF MILWAUKEE, WISCONSIN, ASSIGNOR TO ALLIS-CHALMERS COMPANY, OF MILWAUKEE, WISCONSIN, A CORPORATION OF NEW JERSEY.

ELASTIC-FLUID TURBINE.

No. 863,125.

Specification of Letters Patent.

Patented Aug. 13, 1907.

Application filed June 8, 1906. Serial No. 320,706.

To all whom it may concern:

Be it known that I, WALTER H. WHITESIDE, a citizen of the United States, residing at Milwaukee, in the county of Milwaukee and State of Wisconsin, have invented a certain new and useful Elastic-Fluid Turbine, of which the following is a specification.

This invention relates to turbines, and more especially to elastic fluid turbines such, for instance, as use steam for the working fluid.

10 The object of the invention is to stiffen the rows of blades in either the stator or the rotor, either of these parts being termed the base in the description herein. The rows of blades are usually subjected to vibrations due primarily to the high rate of speed at which the 15 rotor runs. Uneven balancing may also be a cause of vibration. These vibrations may be of such a degree of intensity and of such amount as to be a vital factor for consideration in the design of the machine. The vibration may also be sufficient to affect the securing 20 means of the blades to the base. This vibration of the blades will primarily be in a direction across their thickness. The blades in an action turbine practically extend directly across the row of blades. In a reaction turbine the blades extend at an angle across the 25 row of blades. The vibration therefore in these two types of turbine will differ somewhat. In the action type the vibration which is across the thickness of the blades, will therefore be in the plane of the row of blades. In the reaction turbine the vibration will be 30 across the thickness of the blades and therefore angling across the row of blades, the angle being at right angles to the angle at which the blades are set. The object of this invention therefore is to so stiffen the rows of blades as to lessen or even obviate vibration.

35 In the drawings:—Figure 1 is a broken view of a portion of the base looking longitudinally of the blades and stiffening means. Fig. 2 is a similar view showing a slight modification of the stiffener. Fig. 3 is a side view of a portion of a row of blades in a parallel flow 40 turbine.

The invention is illustrated as applied to a turbine in which the blades are secured to the base. The securing means shown is similar to that shown in the patent to Sankey, Number 797,460, August 15, 1905. 45 This securing means briefly includes a holding ring 1, formed with undercut notches 2. The blades 3 are stamped at their roots so as to fit the notches 2 and also to extend along the side of the holding ring 1. The holding ring 1 is then inserted in a groove in the 50 base 4 with the portion of the blade root extending along the side of the holding ring 1 in contact with a wall 41 of the base. Between the other side of the holding ring 1 and the opposite wall 42 of the groove in the base 4 is placed a calking strip 5 which upon

being calked into place affords a means for tightly securing the blades and holding ring to the base. The wall 41 is usually undercut, as disclosed in the patent referred to.

55 In the practice of this invention, a stiffener 6 is substituted for two or more of the blades. This stiffener is a solid piece preferably formed with two sides corresponding to the inner and outer curved sides of a blade. Its foot or root is calked into place in a similar way to the securing of the blades to the base. It may be inserted between the ends of sections of the holding ring 1, or the holding ring may be suitably slotted for the reception 60 of the root of the stiffener in the same way that the holding ring is formed for the reception of the roots of the blades. It may be found simpler in practice to insert the root of the stiffener between the spaced ends of adjacent sections of holding strip, as illustrated in Fig. 2. The root of the stiffener is tapered so as to fit the undercut wall 41 of the base and may have its sides opposite the blades curved or straight. Ordinarily they could be parallel and straight. The body of the stiffener 65 may extend over the undercut wall 41 to the same extent as the blades ordinarily do, as shown in Fig. 2, or it may extend only to the outer edge of this wall, as shown in Fig. 1.

70 The stiffener 6 may be either of metal drawn in the same way as blades are ordinarily drawn, or it may be formed of cast metal and afterwards shaped to the desired form. In this latter case the curved sides of the stiffener may diverge radially in the case of a parallel flow turbine. The stiffeners 6 may be formed with 75 tenons 61 similar to the tenons 31 formed on the blades. These tenons are formed for the purpose of attaching the baffling strip 7, Fig. 3, similar to the Fullagar baffling strip in common use. The tenon may take up the space ordinarily occupied by two blades, or it may include more than two. It may also be spaced circumferentially around the base in any preferred arrangement. The showing of Fig. 3 is for an arrangement of 80 six stiffeners spaced around the circumference. The stiffeners may be used for both the stator and the rotor, 85 but ordinarily it will be found sufficient to apply them to the rotor only. The showing in Fig. 3 places a stiffener at each of the junctions of the two semi-circular baffling strips 7. In this arrangement the stiffener also serves to unite the semi-circular baffling strip 7 into one 90 100 rigid strip.

It may be convenient, should a drawn stiffener be used, to form its root sectionally, that is, instead of cutting away material to make the root parallel sided, a segmental piece may be applied to the concave side and 105 a filling block between the stiffener and the calking strip 5. The convex side may or may not be cut away, as desired. If it is cut away, the holding ring 1 may be

cut with a plane end to coat therewith. This feature is shown in Figs. 1 and 2. If it is not cut away, the end of the holding ring 1 is preferably concaved to fit the convex side of the root of the holding strip. These considerations of formation and fastening, however, are merely shop expedients in adapting the Sankey fastening, and any convenient specific means may be employed to cause the parts to coat for fastening in the stiffener.

10 The invention is illustrated in connection with blading formed separately and secured to the base, but obviously it is applicable to blading formed in one with the base. In this case the stiffener may also be formed in one with the base but not necessarily so, for it may be 15 secured thereto by any convenient means. Or the stiffener may be formed in one with the base and the blades secured to the base.

It is to be understood that it is not desired to be limited to the exact details of construction shown and described, for obvious modifications will occur to a person skilled in the art.

What is claimed and it is desired to secure by Letters Patent, is:—

1. A base, a row of blades secured to the base, means 25 connecting the blades and a member secured to the base and to said means for stiffening the row of blades.

2. A base, a row of blades secured to the base, means connecting the blades and a stiffening member secured to the base and to said means and located between two blades.

3. A base, a row of blades secured to the base, means 30 connecting the blades and a stiffening member secured to the base and to said means and extending longitudinally of the blades.

4. A base, a row of blades extending from the base, means connecting the blades and a stiffening member extending from the base and secured to said means, said member being located between two blades.

5. A base, a row of blades secured to the base, a member 40 secured to the base and stiffening the row of blades, and means for connecting the blades and member.

6. A base, a row of blades secured to the base, a stiffening member secured to the base and located between two blades, and means for connecting the blades and member.

7. A base, a row of blades secured to the base, a stiffening member secured to the base and extending longitudinally of the blades, and means for connecting the blades and member.

8. A base, a row of blades extending from the base, a stiffening member extending from the base and located between two blades, and means for connecting the blades 45 and member.

In testimony whereof, I affix my signature in the presence of two witnesses.

WALTER H. WHITESIDE.
